UNITED STATES PATENT OFFICE.

JOHN F. LAHART, OF MINNEAPOLIS, MINNESOTA.

METAL-REINFORCED RAILWAY-TIE.

1,071,161.

Specification of Letters Patent.

Patented Aug. 26, 1913.

Application filed December 26, 1911. Serial No. 667,908.

To all whom it may concern:

Be it known that I, JOHN F. LAHART, a citizen of the United States, residing at Minneapolis, in the county of Hennepin and State of Minnesota, have invented certain new and useful Improvements in Metal-Reinforced Railway-Ties; and I do hereby declare the following to be a full, clear, and exact description of the invention, such as 10 will enable others skilled in the art to which it appertains to make and use the same.

My invention has for its object to provide an improved metal reinforced railway tie, and to such ends, generally stated, the invention consists of the novel devices and combinations of devices hereinafter described and defined in the claims.

Particularly, the invention is designed as an improvement on the form of reinforced 20 railway tie disclosed and claimed in my prior Patents 942,267 and 942,268, issued of date December 7th, 1909, and the present features of improvement simplify the construction and increase the efficiency and general 25 practicability of metal reinforced concrete ties.

It is well known that metal reinforced concrete ties, while strong and durable, have, as hitherto constructed, been subject to this 30 serious defect, that they have no resilience, and hence, are the causes of noisy traffic and, furthermore, are hard on the wheels and other parts of the rolling stock. Also, it has been found that where metal is placed directly in contact with the concrete, the 35 weight of the heavy load of trains and the pounding action produced by the heavy rolling stock will crush or crumble the concrete and soon destroy the efficiency of the tie.

As one feature of my present invention, I provide a cushioning plate or body which is formed as a part of the body of the tie and which is interposed between the concrete portion of the tie and the rail or other metallic parts, such as a saddle plate placed 45 directly under the rail.

In the accompanying drawings which illustrate the improved tie, like characters indicate like parts throughout the several 50 views.

Referring to the drawings, Figure 1 is a plan view showing the improved tie; Fig. 2 is a vertical section taken longitudinally through the tie on the line $x^2 x^2$ on Fig. 1; Fig. 3 is a transverse section taken on the line $x^3 x^3$ on Fig. 1; Fig. 4 is a diagram-

matic plan view illustrating a modified arrangement of the tie reinforcement; Fig. 5 is a transverse section taken on the line $x^5 x^5$ on Fig. 4 through a tie designed as illustrated in said Fig. 4; and Fig. 6 is a perspective view showing one of the metal reinforcements used in the tie shown in Figs. 4 and 5.

The concrete body 1 of the tie is formed in its bottom with a concave groove or channel 2 that extends less than from end to end thereof, leaving the end portions of the said tie body flat on their under surface. The sides of the tie body 1 are preferably rounded downward and inward, as shown in Fig. 3. The form thus given to the bottom of the tie body 1 securely anchors the same against movements produced by creeping of the rails or strains longitudinally of the rails, and also decreases the lifting effect produced by heaving of the ground under the action of frost. Also, the tie body thus formed will have a sort of self-tamping action. More particularly stated, after a tie has been settled in the road bed by heavily laden trains, the natural springing in the rail brings the tie back to the level, allowing the loosened ballast or earth to settle back under the tie and thus prevents the tie from being forced deeper and deeper into the bed. The concrete body 1 and its upper face is formed with a longitudinal groove or shallow channel 3 that is widened to the width of the body 1 at points which underlie the rails 4. This channel 3 and its expanded end portions are completely filled with a strong, rough and slightly pliable or resilient composition 5, preferably made as follows: One part of Portland cement, one part of fibrous materials, preferably of asbestos, and three parts of sand, are mixed dry and are then intermingled with hot tar and thus formed into a sort of a mortar or concrete which is pliable while hot, but quickly hardens as it cools.

This filling material, after it is set or hardened, is permanently adhered to the concrete body 1 of the tie, but will always have a very much less rigidity, or in other words, is slightly pliable, but at the same time is tougher and stronger than the concrete of the said tie body 1. It, therefore, forms an efficient cushion between the concrete tie body 1 and the rails.

Metallic saddle plates 6 are set approximately flush into the filling metal 5, and to

anchor the ties to the rails U-bolts 7 are embedded in the said concrete body 1, are extended through the filling material 5 and through the saddle plates 6, and are provided with clamping nuts 8 which, as shown, press washers 9 against the base flanges of the rails. The saddle plates 6, at portions that underlie the rails, are preferably formed with slots 10, through which, portions of the filling material or cushioning plate afforded thereby, project upward into direct contact with the base of the rail. Also, the saddle plates 6 are preferably formed with parallel flanges 11 which hold the rails securely against lateral shifting movements, so that the tie affords an accurate gage in the spacing of the rails. In Fig. 1, the numeral 12 indicates holes or slots in the saddle plates 6, outward of the flanges 11, and through which, other portions of the cushioning plates 5 project upward to the upper surface of the said saddle plates.

The metal reinforcement of the tie is preferably afforded by two quite heavy rods 13, each to form a rectangular loop, the ends of which, as shown, are united at 14. These loop reinforcing rods are set in oblique planes that cross each other transversely of the tie, and the lower rods thereof are embedded in the lower outer portions of the concrete body 1, while the upper rods thereof are embedded in the central portion of the filler or cushioning plate 5. The ends of the said reinforcing loops extend outward toward the ends of the tie considerably beyond the saddle plates 6. The upper rods of the said reinforcing rods or loops 13 are provided with eyes through which, the prongs of the U-bolts 7 are passed. By this arrangement, the tie reinforcing rods are anchored both in the concrete body 1 and in the cushioning or filling plate 5, and are also anchored to the rail anchoring bolts 7. Furthermore, the said reinforcing loops 13 not only reinforce the complete tie after the manner of a truss but securely bind together the various component parts of the tie body. In fact, it will be noted that the lower portions of the reinforcing loops are embedded in the concrete body 1 and the upper portions thereof are embedded in the filler or cushioning plate 5, while the end portions of the said loops are extended obliquely from the said concrete body into the said filler and are there united to the rail anchoring devices.

A tie constructed as above described, is of low enough cost to be not only commercially practicable, but economical because of the long life of the tie. It affords the proper resilience to prevent the tie from being pounded to pieces by the rolling stock, and the cushioning plate or material employed, while it has sufficient strength and rigidity to carry the heavy loads, serves, nevertheless,

less, as an efficient sound deadener and shock or vibration absorber.

In the construction of the tie body, it will usually be found desirable, first to form the so-called cushioning plate or body 5 and then, while the latter is in an inverted position, to form the concrete main body 1, over and around the same. Otherwise stated, the tie body will preferably be formed upside down. This also gives the best opportunity for forming smooth faces on that surface which is to form the top of the complete tie.

In the tie illustrated in Figs. 1, 2 and 3, the saddles in the rails are in the form of flat metal saddle plates, but in the modified arrangement of the tie reinforcement illustrated in Figs. 4, 5 and 6, the rail saddles are formed by bending of the upper portions of the metallic reinforcing loops or rods 13^a, so as to form a rectangular skeleton 13^b. The upper portion of the said reinforcing rod 13^a and the skeleton saddle 13^b are embedded in the cushion plate or metal 5. In Fig. 6, only one of the two reinforcing loops is illustrated, but in Figs. 4 and 5, both thereof are shown. In this modified arrangement, also the upper portions of the reinforcing loops or rods have eyes through which the prongs of the U-bolts 7 are passed.

What I claim is:

1. The combination with a railway tie and rails, of a cushioning plate applied on said tie, and a tie plate seated on said cushioning material, said tie plate having passages through which portions of the cushioning material extend into contact with the bottom of the rail.

2. A railway tie having a concrete body and provided on its upper surface with a cushioning plate extended from one rail support to the other, and rail anchoring devices embedded in said concrete body and cushioning plate and projecting above the latter.

3. A railway tie having a concrete body and provided on its upper surface with a cushioning plate extended from one rail support to the other, and metallic reinforcing rods extended in part through said concrete body and in part through said cushioning plate.

4. A railway tie having a concrete body and provided on its upper surface with a cushioning plate extended from one rail support to the other, rail anchoring devices embedded in said concrete body and reinforcing plate, and metallic reinforcing loops embedded in part in said concrete body and in part in said cushioning plate and anchored to the said rail anchoring devices.

5. A railway tie having a concrete body and provided on its upper surface with a cushioning plate extended from one rail support to the other, rail anchoring devices embedded in said concrete body and rein-

forcing plate, and metallic reinforcing loops embedded in part in said concrete body and in part in said cushioning plate and anchored to the said rail anchoring devices, 5 and metallic rail saddles located on the upper surface of said cushioning plate and through which said rail anchoring devices are passed.

6. A railway tie having a concrete body

and having rail supporting sections constructed of a material composed of cement, sand, tar and a fibrous substance. 10

In testimony whereof I affix my signature in presence of two witnesses.

JOHN F. LAHART.
